UNITED STATES PATENT OFFICE.

LEWIS E. PEASE, OF WEST SOMERVILLE, MASSACHUSETTS.

FOUNTAIN-SYRINGE.

1,093,353.

Specification of Letters Patent. Patented Apr. 14, 1914.

Application filed March 19, 1913. Serial No. 755,352.

To all whom it may concern:

Be it known that I, LEWIS E. PEASE, a citizen of the United States, residing at West Somerville, county of Middlesex, State 5 of Massachusetts, have invented an Improvement in Fountain-Syringes, of which the following description, in connection with the accompanying drawing, is a specification, like characters on the drawing representing like parts.

This invention relates to fountain syringes and has for its object to provide a fountain syringe with a novel tube support on which the eduction tube can be sustained in such a 15 way as to prevent it from becoming broken by having a sharp bend made therein.

In common practice fountain syringes are hung from a hook or nail, and when the syringe is not in use the eduction tube is frequently hung up over the supporting hook or nail. When this is done a sharp bend is given to the tube where it engages the nail, which very soon breaks or cracks it at this point.

25 My invention aims to obviate this difficulty by providing a tube support which will hold the tube in such a way that there will be no danger of its becoming broken or injured.

30 In the drawings wherein I have shown some preferred embodiments of my invention, Figure 1 is a view of a fountain syringe embodying the invention showing the manner in which the tube is supported by the tube support; Fig. 2 is an enlarged section 35 on the line $\alpha-\alpha$, Fig. 1; Fig. 3 is a view similar to Fig. 2, but showing a different embodiment of the invention.

1 designates the bag or water-containing 40 receptacle of the fountain syringe, and 2 the usual eduction tube which is provided with the shut-off 3 and a removable tip 4 as usual. These parts are such as are usually found in fountain syringes and form no part 45 of my present invention.

50 My syringe is formed with a tube support shown generally at 5 which is of such shape and dimensions as to support the tube 2 without forming a sharp bend therein. This tube support is preferably associated with the supporting tab 6 with which fountain syringes are usually provided and by which they are sustained. The tube support may be either made integral with the tab or may 55 be a separate part secured thereto. In Fig. 2 I have shown it as integral with the tab,

said tab being molded to present the boss or thickened portion 5 which is preferably circular in shape and is provided on its periphery with a tube-receiving groove 7 of 60 a size to receive the tube 2, as clearly shown in Fig. 2. The tube support 5 and tab 6 are provided with an aperture 8 to receive the hook, nail or other supporting device for the syringe, and I will preferably provide this aperture with a metal lining which can be done by inserting an eyelet 9 therein of the proper shape. This eyelet is provided with the flange 10 which embraces the front face of the tube support and with the flange 11 on the other end which overlies and embraces a washer or grommet 12. The eyelet 9 serves not only to provide a metal lining for the aperture 8, but it also serves as a reinforcing means for the tube support 5 65 and serves to hold the tube support in its proper shape.

In Fig. 3 the tube support 50 is separate from the tab 6, it being in the nature of a filling of rubber or other material which is applied to the face of the tab 6 and is held thereto by the eyelet 9, said eyelet having the same construction as that described with reference to Fig. 2. The construction shown in Fig. 3 makes it possible to apply my improved tube support to any ordinary fountain which is provided with the supporting tab 6. This can be done by merely providing the filling piece 50 of the proper shape and securing it to the tab by the eyelet 9. 70 75 80 85

One advantage of making the tube support in connection with the supporting tab 6 is that when the tube 2 is resting on the support the end of the tube can be placed within the bag 1, thus avoiding all danger of 90 dripping.

While I have illustrated some embodiments of my invention, I do not wish to be limited to the constructional details shown.

Having fully described my invention what 100 I claim as new and desire to secure by Letters Patent is:

1. In a fountain syringe, the combination with a bag and an eduction tube connected thereto, said bag having at its upper end a supporting tab of moldable material which has molded integral therewith a tube support presenting a tube-receiving groove having a contour corresponding to the exterior of the tube. 105

2. In a fountain syringe, the combination with a bag and an eduction tube connected 110

thereto, said bag having a supporting tab at its upper end, of a tube support on said tab, said tab and support having an aperture extending therethrough to receive a hook or other supporting means.

3. In a fountain syringe, the combination with a bag and an eduction tube connected thereto, said bag having a supporting tab at its upper end, of a tube support on said tab, said tab and support having a metal-lined aperture extending therethrough to receive a hook or other supporting means.

4. In a fountain syringe, the combination with a bag and an eduction tube connected thereto, said bag having a supporting tab

at its upper end, of a tube support on said tab, said tab and support having an aperture extending therethrough to receive a hook or other supporting means, and a metal eyelet lining said aperture and provided 20 with a flange which embraces the tube support and holds it in the desired shape.

In testimony whereof, I have signed my name to this specification, in the presence of two subscribing witnesses.

LEWIS E. PEASE.
